(57) **CLAIM**

The ornamental design for a bra, as shown and described.

DESCRIPTION

FIG. 1 is a front view of a bra according to the design; FIG. 2 is a rear view thereof; and, FIG. 3 is a rear view thereof shown in an environment of use. The broken line outline of the partial human figure in FIG. 3 assists in illustrating how the bra may appear when in a position of use, but forms no part of the claimed design. The broken lines along the surface of the bra depict feature lines of the article that form no part of the claimed design. The cross hatching represents a contrast in appearance only.
